JARRING TOOLS

Ralph M. Turner, Washington, D. C.

Application June 11, 1956, Serial No. 590,759

3 Claims. (Cl. 1—47)

This invention relates to new and useful improvements and structural refinements in jarring tools or percussion tools adapted for attachment to a conventional electric drill for converting the rotary motion thereof into a reciprocating movement with a definite impact during each stroke, whereby the tool may be effectively employed for driving nails and numerous other, similar operations. More specifically, this invention is an improvement on my original invention forming the subject matter of my co-pending application Serial No. 469,229, filed November 16, 1954, now Patent No. 2,749,548, issued June 12, 1956, of which this application is a continuation-in-part.

While experimenting with the invention according to my earlier application, I found that the same lends itself to various structural simplifications which result in greater economy of manufacture and greater durability without impairing efficiency of operation. It is, therefore, the principal object of the instant invention to provide a tool wherein such improvements are embodied.

With the above more important object and features in view and such other objects and features as may become apparent as this specification proceeds, the invention resides in the arrangement of parts and details of construction substantially as shown in the accompanying drawing, wherein like characters of reference are used to designate like parts and wherein:

Figure 1 is a longitudinal sectional view of my improved tool;

Figure 2 is a fragmentary longitudinal sectional view thereof with the cam follower and shaft in the retracted position;

Figure 3 is a transverse sectional view, taken substantially in the plane of the line 3—3 in Figure 1;

Figure 4 is a perspective view of the housing extension and cam member integral therewith;

Figure 5 is a group perspective view of the shaft, cam follower, adapter and sleeve used in the invention; and

Figure 6 is a perspective view of the work guide.

Referring now to the accompanying drawing in detail, the jarring tool is designated generally by the reference numeral 10 and embodies in its construction an elongated housing 11 comprising a main body portion 12 which is enlarged at one end thereof as shown at 12a to receive a conventional electric drill 13, the latter being secured therein by one or more set screws 14. The housing 11 also includes an extension 15 which is removably connected to the other end of the portion 12 by screw threads 16.

The extension 15 is formed integrally with a cam member 17 disposed within the housing, this cam member having lobes 18 with high and low dwells 18a, 18b, respectively, as is best shown in Figure 4. The extension 15 is also provided with inner and outer counterbores 19, 20, respectively, affording a bearing portion 21 therebetween.

A shaft 22 is rotatably and slidably disposed in the bearing 21, the outer end of this shaft having a work engaging face 23 while the inner end portion of the

shaft is provided with an open-sided slot 24. Moreover, a transversely extending cam follower 25 is formed integrally with the intermediate portion of the shaft and is operatively engageable with the cam member 17. As is best shown in Figure 5, the opposite corner portions 26 of the cam follower 25 are rounded so as to facilitate their passage over the cam member lobes 18 in a sliding fashion.

5 The housing portion 12 is provided with a transverse partition 27 having an aperture therein which affords a bearing 28 for a shaft-like adapter 29, one end portion of the latter being engageable with the chuck 30 of the drill 13, while its other end is provided with a substantially flat, longitudinally projecting tongue 31. The tongue 31 is slidably but non-rotatably disposed in the aforementioned slot 24 of the shaft 22, whereby the shaft is rotatable with the adapter 29 and, at the same time, may slide longitudinally relative thereto.

10 The intermediate portion of the adapter 29 is formed with a shoulder 32 disposed at one side of the partition 27, while a snap ring 33 is positioned in a groove 34 of the adapter at the opposite side of the partition, to prevent the adapter from sliding in the bearing 28. It is to be noted that the partition 27 is provided with a 15 counterbore having an oil seal 35 positioned therein, so that lubricant placed in the housing cannot leak past the bearing 28 into the housing portion 12a. The housing portion 12 is provided with a suitable opening 36 to facilitate insertion of a key to manipulate the drill 13, chuck 30, and, also, to facilitate installation or removal of the snap ring 33. Lubricant may be placed in the housing upon removal of the housing extension 15.

15 In order to maintain the adapter 29 and the shaft 22 in axial alignment, a tubular keeper sleeve 37 is positioned on the shaft so that it extends over the slot 24 and the tongue 31. A relatively strong coil spring 38, in turn, surrounds the sleeve 37 and extends between the partition 27 and the cam follower 25, whereby to urge the latter in engagement with the cam member 17.

20 A relatively weak shock absorber spring 39 is positioned in the counterbore 19 of the housing extension 15 on the shaft 22 and in engagement with the bearing portion 21, this spring also being engageable by the cam follower 25 as will be hereinafter described. The outer 25 counterbore 20 of the extension 15 slidably receives a projectable and retractable work guide 40 of a tubular form, the same being urged outwardly by a spring 41 in the counterbore 20, this arrangement being substantially the same as in my Patent No. 2,749,548. The guide 40 is in surrounding relation to the work engaging face 23 of the shaft 22 and is retained in the extension 15 by an internal nut 42 threaded as at 43 into the counterbore 20. As is best shown in Figure 6, the inner end 50 of the guide 40 is provided with an outturned shoulder 44 to abut the spring 41.

25 Having thus described the construction of the invention, its operation will now be explained.

30 Assuming the tool to be in its initial position as shown in Figure 1 with the cam follower 25 having its rounded corner portions 26 substantially in alignment with the low dwells 18b of the cam member 17, rotation of the adapter 29 and shaft 22 will cause the follower 25 to ride along the cam lobes 18 with the result that the follower as well as the shaft 22 will be retracted to the position shown in Figure 2 wherein the follower engages the high dwells 18a of the cam member 17. At the same time, the spring 38 will be compressed, and as rotation of the shaft 22 continues, the follower 25 will slide off the high dwells 18a and under the action of the 35 strong spring 39 will be driven forwardly, thus correspondingly driving the face 23 of the shaft 22 against the work. As is best shown in Figures 2 and 4, the cam

member 17 is provided between the adjacent high and low dwells of the lobes 18 with recesses 45, which permit the follower 25 to be driven forwardly by inertia, beyond the low dwells 18b, so that the maximum forwardly projected position of the shaft face 23 is as indicated by the dotted line 46 in Figure 1. The shock absorber spring 39 is of such length that it does not become compressed until the follower 25 moves into the recesses 45 and, when the forward driving force of the follower is expended, the spring 39 will automatically return the follower and the shaft 22 to its initial position as shown in Figure 1.

The guide 40, surrounding the work engaging face 23 of the shaft 22, will effectively prevent the tool from sliding or slipping laterally off the work and, since the guide is retractable into the extension 15, flush driving of a nail or other work will be facilitated.

The thread 16 connecting the extension 15 to the housing portion 12 is preferably left-hand thread, so that it has the tendency to tighten itself by the rotating engagement of the follower 25 with the cam member 17 of the extension 15. To avoid undue friction between the rotating follower 25 and the relatively non-rotatable spring 38, a suitable thrust bearing 47 is positioned in a recess 48 formed in the follower 25, as is best shown in Figure 2.

While in the foregoing there has been shown and described the preferred embodiment of the invention, various modifications may become apparent to those skilled in the art to which the invention relates. Accordingly, it is not desired to limit the invention to this disclosure, and various modifications may be resorted to, such as may lie within the spirit and scope of the appended claims.

What is claimed as new is:

1. In a jarring tool, the combination of an elongated housing including a main body portion adapted at one end thereof for attachment to an electric drill and an extension provided at the other end of said main body portion, a cam member formed integrally with said extension and disposed in said housing, a shaft extending rotatably and slidably through said extension and having a work engaging face at its outer end, a drill engaging adapter rotatably mounted in said main body portion of said housing, means slidably connecting the inner end of said shaft to said adapter for rotation therewith, a

cam follower provided intermediate the ends of said shaft and operatively engaging said cam member whereby the shaft is reciprocated during rotation thereof, a coil spring provided in said housing and engaging said cam follower to urge the same against said cam member, and a shock absorber spring interposed between said extension and said cam follower.

2. In a jarring tool, the combination of an elongated housing including a main body portion adapted at one end thereof for attachment to an electric drill and an extension provided at the other end of said main body portion, a cam member formed integrally with said extension and disposed in said housing, a transverse partition provided in the main body portion of the housing and formed with an aperture affording a bearing, a shaft extending rotatably and slidably through said extension and having a work engaging face at its outer end, a drill engaging adapter rotatably mounted in said bearing, means slidably connecting the inner end of said shaft to said adapter for rotation therewith, a cam follower formed integrally on an intermediate portion of said shaft and operatively engaging said cam member whereby the shaft is reciprocated during rotation thereof, a relatively strong coil spring provided in said housing between said partition and said cam follower for urging the latter in engagement with said cam member, and a relatively weak shock absorber spring interposed between said extension and said cam follower.

3. The device as defined in claim 2 wherein said means for connecting said shaft to said adapter comprise a projecting tongue formed integrally with said adapter, the inner end portion of said shaft being provided with a slot having said tongue slidably but non-rotatably disposed therein, and a tubular keeper sleeve positioned on and embracing the slotted portion of said shaft and said tongue whereby to assist in maintaining the same in alignment, said relatively strong coil spring surrounding said keeper sleeve.
